UNITED STATES PATENT OFFICE.

WARD S. CRAWFORD, OF OTTAWA, KANSAS.

DOOR-MOUNTING MEANS.

Application filed May 16, 1927. Serial No. 191,878.

The invention relates to the hanging of doors in such manner that they may move laterally into or out of their frames and when moved outwardly, may slide in planes parallel with said frames. The invention further relates to mounting means of the type embodying a track above the door, carriages movable along said track, and horizontally swingable arms pivoted on vertical axes to the door and the carriages, the arms, track and carriages serving as supporting means for the door while the latter is being opened and closed. The track is necessarily spaced outwardly from the plane occupied by the door when in its closed position and if the above named parts were then permitted to act as suspending means for the door, the latter would not hang in a strictly vertical plane with the frame, but its lower end would necessarily swing outwardly, due to the manner in which the center of gravity would then act. It is one object of my invention however, to overcome this tendency by the provision of co-acting means on the upper ends of the door and frame for suspending said door independently of the arms, carriages and track, when said door is in its closed position, said co-acting means being so positioned with regard to each other, as to cause the center of gravity to insure hanging of the door in a strictly vertical plane.

It is another object of the invention to provide a generally simplified, yet an efficient construction for the door hangers, of such nature as to permit desired vertical adjustment of the door when initially hanging it or later if desired.

With the foregoing in view, the invention resides in the novel subject matter herein-after described and claimed, the description being supplemented by the accompanying drawings.

Fig. 1 is a perspective view with the door closed.

Fig. 2 is a similar view with the door partly open.

Fig. 3 is a vertical transverse section on line 3-3 of Fig. 1.

Fig. 4 is a detail view similar to a part of Fig. 3 but showing the door moved out of the frame.

Fig. 5 is a horizontal sectional view on line 5-5 of Fig. 3.

Fig. 6 is a disassembled perspective of one of the hangers.

In the drawings above briefly described, 10 denotes a vertical wall having a door opening 11, and 12 denotes a door movable into and out of said opening, the edge wall 60 of said opening forming part of a door frame, whose remainder is constituted by appropriate framing bars 13 secured to the inner side of the wall 10 and positioned to abut the door 12 when the latter is closed. 65

Suitably mounted in any desired manner upon the wall 10, at the upper end of the door frame, is a horizontal track 14 which is outwardly spaced from said wall. A suitable number of carriages 15 are supported by this track, and horizontally swingable arms 16 have pivotal connections at one end with the carriage and at their other ends are similarly connected with the door 12, the pivotal or hinge axes being disposed vertically. When the door 12 is moved laterally into or out of the frame, the arms 16 swing about their pivots, and as the door is slid from one position to another, its weight is supported by the arms and carriages, upon the track 14.

When the door stands closed, the carriages 15 are necessarily outwardly spaced from the plane which said door then occupies. Hence, if the door were then supported by the arms 85 16 and carriages 15, the center of gravity would be such as to cause the lower end of the door to swing outwardly from the frame. Hence, I provide co-acting means at the upper ends of the door and frame to so shift the 90 center of gravity as to cause vertical hanging of the door, said co-acting means then supporting the weight of the door independently of the carriages 15, track 14 and arms 16.

In the present showing, a transverse horizontal finger 17 is rigidly secured by bolts or the like 18 to the uppermost of the frame members 13, so that its free end projects outwardly. The upper end of the door 12 is provided with a roller 19 whose axis is horizontal, extends in a plane parallel with the opposite sides of the door, and is preferably located nearer to the inner side of said door than to the outer side thereof. This roller when the door is closed, rests upon the rigid finger 17 and hence suspends the weight of the door 12 independently of the parts 14, 15 and 16, and by positioning said roller in the manner described, the center of gravity is such as to cause strictly vertical hanging of the door 12. 105 110

Preferably, the roller 19 is mounted in a

U-shaped bracket 20 suitably secured in a notch 21 in the upper end of the door 12. One or more of these rollers and an equivalent number of the fingers 17 may be employed, according to the length of the door 12.

The carriage 15 herein shown, is provided with two rollers, but in so far as certain features of construction are concerned, said carriage might in some instances have other numbers of rollers or in fact only one. This carriage is provided with a laterally projecting portion 22 having a vertical opening 23, and one end of the arm 16 is disposed below said laterally projecting portion and provided with a vertical bearing 24 alined with said opening 23, the other end of the arm being provided with appropriate means 25 for connecting it to the door 12. A vertical hanger bolt 26 passes through the bearing 24 and the opening 23, the lower end of said bolt being provided with a head 26^a upon which the bearing 24 rests, while the upper end of said bolt is provided with adjusting nuts 26^b which contact with the upper and lower sides of the projecting carriage portion 22. These nuts permit vertical adjustment of the hanger bolt 26, as occasion may demand, and by then tightening both of said nuts, the bolt 26 is held against turning, so that the bearing 24 may turn upon it as the arm 16 horizontally swings.

In the form of construction herein disclosed, the projecting carriage portion 22 is formed by a rectangular metal block contacting with the outermost of two horizontally elongated plates 27-28, between whose ends track wheels or rollers 29 are mounted. Between the intermediate portions of these plates 27-28, is a spacing block 30. A pair of transverse bolts 31 pass through alined openings in the blocks 22-30 and the plates 27-28, the openings of the parts 22-27-28 being indicated at 22^a, 27^a and 28^a respectively. The openings of the spacing block 30 are by preference in the form of grooves 30^a, although such formation is not absolutely essential. The bolts 31 rigidly secure the

parts 22-27-30-28 together and hence a very rigid hanger construction is provided and one which may be easily and inexpensively manufactured.

A suitable angular shoe 32 is preferably secured to the plate 27 to underlie the track 14, preventing possible jumping of the carriage therefrom.

If desired, suitable trackage 33 may be provided at the lower end of the door frame to limit the outward movement of said door and to otherwise assist in guiding the latter. Moreover, any desired locking means may be employed for holding the door in closed position. This locking means constitutes no part of the present invention and hence is not described in detail, although it may be considered that wherever the number 34 appears on the drawings, it indicates a part or parts of said locking means.

I claim:

1. In combination, a door frame, a door of a size to fit therein, a track at the upper end of said frame spaced outwardly from the outer side thereof, carriages mounted on said track, horizontally swingable arms pivoted to said carriages and to the door on vertical axes, and co-acting means on the upper ends of the frame and door for suspending the latter independently of the carriages when said door is closed, said co-acting means being related to cause hanging of the door in a strictly vertical plane.

2. In combination, a door frame, a door of a size to fit therein, a track at the upper end of said frame spaced outwardly from the outer side thereof, carriages mounted on said track, horizontally swingable arms pivoted to said carriages and to the door on vertical axes, a rigid transverse finger secured to the crown of the door frame, and means on the door to rest upon said finger and suspend said door independently of the carriages when the door is closed, said means being positioned to cause hanging of the door in a strictly vertical plane.

In testimony whereof I have hereunto affixed my signature.

W. S. CRAWFORD.
